(No Model.)

G. M. HOPKINS.
TURBINE.

No. 521,713.

Patented June 19, 1894.

UNITED STATES PATENT OFFICE.

GEORGE M. HOPKINS, OF NEW YORK, N. Y.

TURBINE.

SPECIFICATION forming part of Letters Patent No. 521,713, dated June 19, 1894.

Application filed December 14, 1893. Serial No. 493,624. (No model.)

To all whom it may concern:

Be it known that I, GEORGE M. HOPKINS, of New York city, in the county and State of New York, have invented a new and Improved 5 Turbine, of which the following is a specification, reference being had to the annexed drawings, forming a part thereof, in which—

Figure 1 is a front elevation of my improved turbine. Fig. 2 is a face view of one half of the 10 turbine wheel. Fig. 3 is a diametrical section of the wheel. Fig. 4 is a central longitudinal section of the nozzle. Fig. 5 is a front elevation of the same. Fig. 6 is a rear elevation of the nozzle; and Fig. 7 is a longitudinal section 15 of a double nozzle for a reversing turbine.

Similar letters of reference indicate corresponding parts in all the views.

The object of my invention is to construct a turbine—to be used with steam, water or 20 compressed air as the propelling force—which is formed with a smooth, uninterrupted exterior surface which will offer a minimum of resistance to the air, and in which the nozzle through which the propelling medium is 25 ejected will be partly surrounded by the propelling wings.

My invention consists in a wheel having a 30 smooth exterior and an annular chamber containing wings for receiving the impact of the propelling medium, and having a central free space for the ejector nozzle.

It also consists in a nozzle constructed to 35 project steam in a thin wide stream against the wings, and arranged to draw the air from behind the nozzle by induction and project it in a stream impinging on the jet of steam.

The invention also further consists in a 40 double nozzle arranged to discharge the propelling medium in either direction for the purpose of reversing the turbine.

It also further consists in a turbine formed 45 of aluminum, for the purpose of reducing the weight and facilitating the reversal of the turbine.

In describing my invention I shall refer to 50 it as a steam turbine, although I do not limit myself to the use of steam as a motive agent. I shall also describe the turbine as having an annular space of circular cross section, for containing the steam nozzle, but I do not confine myself to this particular form.

Upon the shaft A, journaled in the frame

B, is mounted the turbine wheel C which is formed of two similar halves a a', each provided with a boss b, and having a web c and rim d of approximately semi-elliptical form, the two halves a a' being oppositely arranged with respect to each other and fastened upon the shaft by means of the nut e which clamps the wheel against the collar f formed on or attached to the shaft. The semi-elliptical half rims d, when placed together, form a practically elliptical rim, in the center of which is formed an annular space g of circular cross section, and on opposite sides of the said annular space g, the rim is cut away by means of a suitable milling cutter, leaving the inwardly-projecting wings h which extend from a point near the periphery of the wheel to a point within the annular space g.

In cutting away the interior of the rim to form the wings h, intermediate wings h' are formed, which are shorter than the wings h and project inwardly from the outer portion of the wheel. This arrangement will be followed in the construction of very small turbines, but in larger turbines where the wings h are more nearly parallel, the intermediate wings h' may be omitted.

From the periphery of the turbine wheel 80 down to the annular space g is formed a slot j for receiving the plate D, which supports the nozzle E and the pipe k. The plate D is rigidly supported in such relation to the wheel C, as to allow the wheel to revolve freely 85 without coming into contact with the plate. The nozzle E is made annular, with the steam space l having an annular discharge opening m, the steam space l communicating with the pipe k. Within the annular steam space l is 90 a longitudinal opening n, partly closed by a cone o, leaving an annular space p, the cone being held in its position by distance pieces q, and retained by a bolt r which passes through a cross bar s extending across the 95 rear end of the nozzle E.

Although I have fully shown but a single nozzle in the drawings, in practice the turbine will have two or more nozzles, as indicated by dotted lines; and furthermore, where it is 100 desirable to reverse the turbine, the nozzle is made double, as shown in Fig. 7, having two supply pipes k, k', two annular steam spaces l l', two annular discharge openings m m' and

two annular spaces p p' . The annular spaces m m' and p p' open in opposite directions. Steam admitted to the nozzle E through the pipe k , enters the annular space l , and is distributed, and discharged through the annular opening m , the discharge opening being of such character as to give to the annular jet of steam a divergent form, causing it to strike the wings h h' . In issuing from the annular opening m , the steam by induction draws air through the annular space p , thus withdrawing the air from behind the nozzle and projecting it against the annular stream of steam. This arrangement to a great extent removes the back pressure of air behind the nozzle, and its projection in a stream more divergent than that of the steam causes it to act to some extent as an abutment for the steam, for holding it against the wings h h' .

20 When the turbine is to be made reversible, the double nozzle shown in Fig. 7 is used and steam is admitted to one or the other of the parts of the nozzle according to the direction in which the wheel is to revolve. To facilitate the reversal of the turbine, the wheel of a reversible turbine is made of aluminum, thus reducing the momentum of the wheel, so that it may be more readily stopped, and started in the opposite direction. Where the 25 turbine is not intended to be reversible, it is preferably made of bronze or some unoxidizable material having sufficient strength.

It will be seen that my improved turbine offers no roughness or projections on the exterior to act upon the air and thus cause resistance. The wheel having wings which are practically radial, and being provided with a peripheral groove for the discharge of the contents of the hollow rim, when it revolves 30 at a high velocity a partial vacuum is formed by centrifugal force, which adds to the efficiency of the turbine by removing air resistance. Centrifugal force also throws out every particle of water resulting from the condensation of steam.

45 Having thus described my invention, I claim as new and desire to secure by Letters Patent—

1. A turbine wheel, having a smooth uninterrupted exterior and provided with an annular space with its sides surrounded by wings except at its point of support having at the sides thereof wings for receiving the impact of the propelling medium, and a nozzle held 50 wholly within the annular space and constructed to project a thin wide jet of steam against the wings, as specified.
2. The combination, with a wheel having a hollow rim with an annular space, and wings 55 projecting into the annular space and furnished with a groove extending from the periphery of the wheel to the annular space, of

an annular nozzle supported within the annular space and provided with two concentric annular apertures, one for projecting 65 steam against the wings and the other for the passage of air, from the rear to the front of the nozzle as herein specified.

3. A turbine wheel formed of two like halves both placed on the shaft and oppositely arranged with respect to each other each half being separately supported by the shaft, the division line between the halves being in the plane of rotation of the wheel, the said halves being mounted rigidly on a shaft, in contact 70 with each other, the complete wheel having a hollow rim with inwardly-projecting wings, substantially as specified.

4. In a turbine, a wheel having a hollow rim provided with inwardly-projecting wings, and having a groove extending from the periphery of the wheel inwardly, the groove being enlarged within the rim of the wheel, forming a passage for the nozzle, a nozzle placed in the said passage and constructed to direct a thin 80 stream of steam against the wings, and furnished with an opening from front to rear for the passage of any fluid or liquid from the rear of the nozzle to the front thereof, as specified.

5. A turbine, formed of a wheel having a hollow rim with inwardly-projecting wings, and provided with openings through the wings which form an annular passage through the hollow wheel rim and wings contained thereby, the wheel having a peripheral groove extending to and communicating with the annular passage, and a nozzle supported within the annular passage of the wheel rim and adapted to direct a jet of steam against the inwardly projecting wings, substantially as 90 specified.

6. In a steam turbine, the combination with a wheel having a hollow rim with inwardly-projecting wings, of an ejector nozzle placed within the hollow rim and having two concentric annular openings, the outer one being for the discharge of steam under pressure and the inner one being for removing air, steam or water from the rear of the nozzle on the ejector principle, substantially as specified. 105

7. The combination, with a turbine wheel having a hollow rim containing inwardly projecting wings and provided with an annular passage parallel with the plane of rotation, of an annular nozzle supported within the annular passage and arranged to discharge a thin stream of steam in a direction tangential to the path of the inner edges of the wings, substantially as specified. 115

ALBERT A. HOPKINS.

Correction in Letters Patent No. 521,713.

It is hereby certified that in Letters Patent No. 521,713, granted June 19, 1894, upon the application of George M. Hopkins, of New York, N. Y., for an improvement in "Turbines," an error appears in the printed specification requiring correction as follows: Page 2, lines 51-52, the clause "with its sides surrounded by wings except at its point of support," should be stricken out and inserted after the word "space," line 55 as now numbered, same page; and that the Letters Patent should be read with this correction therein that the same may conform to the record of the case in the Patent Office.

Signed, countersigned, and sealed this 10th day of July, A. D. 1894.

[SEAL.]

JNO. M. REYNOLDS,
Assistant Secretary of the Interior.
